UNITED STATES PATENT OFFICE.

MATTHEW TROY, OF PORTLAND, OREGON.

SACK LADDER.

Application filed November 3, 1921. Serial No. 512,472.

To all whom it may concern:

Be it known that I, MATTHEW TROY, a citizen of the United States, and a resident of the city of Portland, county of Multnomah, 5 and State of Oregon, have invented a new and useful Improvement in a Sack Ladder, of which the following is a specification.

In loading a ship with sacked material, for example flour, prior to my invention, it 10 was common to employ a chute or similar device down which the sacks were permitted to slide. But the speed at which the sacks descended caused them to impact with such force against any obstruction in their 15 path that they frequently burst. To avoid this, a stevedore was stationed to stop or check the speed of the sack before striking such obstruction. To eliminate the need of such stevedore a chute or so-called sack 20 ladder was invented as shown by U. S. patent granted to F. W. Brink, No. 707,297, August 19, 1902, for an improvement in chute for loading wheat or flour on ships. But such sack ladder was impracticable, because of the abrupt variations in the angles 25 which the planes of the surfaces along which the sacks slid made with each other, requiring the body of the sack to assume sudden changes in form, and thus having imposed upon the material of which the 30 sacks were made such strains as frequently to cause the sacks to burst when diverted from one step to another.

In other words when the sack had slid down one step its body would have to assume a sharp curve the instant it is diverted to the next step; but its momentum would be so great that it could not assume the required curved form at the instance of impact with the surface diverting it to the 40 next step, and in consequence the sack would tend to burst.

I discovered that such bursting of the sacks could be avoided by changing the 45 relative angle of the consecutive planes of the surfaces over which the sacks glide. In short, I discovered that the planes of said surfaces should be so arranged as to make obtuse angles with each other; in that 50 way eliminating all abrupt, extreme changes in the form of the sacks, and permitting them gradually to change from one form of curvature to another.

Furthermore, I have discovered that the 55 interior should not have any projections ex-

tending upwardly from the walls, because the sacks are apt to strike such projections and to be injured and burst by so doing.

I attain my object by the device illustrated in the accompanying drawings in which Fig. 1 is a perspective of my sack ladder, in this instance comprising only a single section, and the representation in this figure assuming that my sack ladder is suspended from coaming of the upper deck in position for discharging into the hold of the vessel.

Figs. 2 and 2^A are vertical sections of my sack ladder, in this instance showing the same as made of 3 sections which are separated for convenience of handling and storing.

Fig. 3 shows a vertical section of my sack ladder which, in this instance, is illustrated as composed of only one section; it is assumed that the sack ladder is suspended by similar means as shown in Fig. 1, and this view illustrates the construction of the interior, and the manner in which the sack passes over the steps in descending the ladder.

Fig. 4 is a vertical section looking in the direction pointed by the arrow 4 in Fig. 3, and Fig. 5 is a cross section on the line 5—5 of Fig. 3.

My sack holder comprises a rectangular casing *a* which, when constructed of wood, may be made of exterior pieces *b*, arranged crosswise, and interior piece *c* arranged vertically; but any construction will suffice which will tend to offer a smooth surface and little resistance to the passage of the sacks.

On the exterior of the casing, I provided eyes *d* and *e* for fixing suspended cables or chains as *f* and *g*. *h* represents the coaming of the upper deck. A chute *i* in part supported on a horse *j* discharges into the upper end of my sack ladder. The upper end is preferably provided with flaring sides providing a sort of hopper top.

On the interior of the casing *a* I provided a plurality of steps *l* and *l'* which may consist of angle irons *m* and suitable flooring secured on these angle irons or merely flanged plates.

The steps project from the interior of the opposite walls of the casing. The steps are downwardly inclined toward each other as more clearly shown in Figs. 2 and 3; and the ends of the steps overlap slightly and

are spaced from the opposite wall so as to provide a passageway for the sacks as illustrated in Fig. 3.

It is to be noted that the lower ends of the steps are spaced from the opposite side wall and from the top of the next lower step relatively to the length and thickness of the sack, in order that the latter will be caused to bear continuously on the steps and opposite wall surfaces, successively, in passing; and by these means the speed of motion of the sack is constantly restrained by the incidental friction between the sack surfaces and the surfaces over which it travels.

As mentioned, I prefer to make my sack ladder in sections, so that the length thereof may be adjusted to circumstances. For example, referring to Fig. 2 the upper section a'' may be made of a length so as to pass the sack from the upper deck to the intermediate deck; this top section a'' being suspended from the coaming of the upper deck; and the intermediate section a' may be suspended from the coaming of the intermediate deck, or from the upper section, and carries the sack into the lower section a^2 , and through the latter into the hold of the vessel.

When my sack ladder is made in sections these sections must be so proportioned with respect to length and location of the steps in the connected ends of the chute as to adapt the latter steps to function as described.

A deflector chute o is suspended adjacent to the lower step l^2 and this deflector chute o in turn discharges on a longer chute p .

In order to support the upper end of the deflector chute o , I provide a pair of arms q having interior projecting pins r , on which to hang the hook irons s provided on the underside of the chute o .

I provide suitable hand holes t under the steps so that any sack which might become lodged can be loosened and removed without loosening the rigging.

I have experimented with my gravity conveyor in the conducting of standard grain sacks and flour sacks in the 3 standard sizes, 50 lbs., 100 lbs. and 140 lbs., and standard sugar sacks, and have constructed my casing 25" in width and length with the steps 18" wide and the full length across

of 25". These extend at approximately 45° from the side of the casing and will overlap the center line 1".

As is shown in Fig. 2, the distance marked x or the distance downward between the ending of the upper step to the beginning of the lower step is 14". These distances I have found, transmit the correct wave-like motion of the sack when descending the ladder.

Besides it is to be noted from Figs. 2 and 3 that if the plane of an upper step were extended so as to intersect the plane of the adjacent opposite wall, and a similarly intersecting line were drawn parallel with said plane, spaced therefrom to represent the thickness of the sack, the intersections would occur some distance above the plane of the next lower step projecting from said wall; and the said intersecting planes would make an obtuse angle with each other. In that way the desired effects described in the introduction of the specification are caused.

The illustrations and description above given are merely intended to show a practical mode of construction of my device. The particular details of construction above described are, however, variable to suit the ideas of manufacture providing such variation retains the essential features of my invention.

I claim:

A sack ladder comprising an elongate casing of rectangular cross section, a series of inclined steps projecting alternately from opposite walls of the casing and extending part way across the space separating said walls, said steps being so relatively arranged that the plane of the tread of an upper step, if extending to the opposite wall, would intersect the latter some distance above the point from which the next lower step projects from such wall, thereby providing a wall surface above said point against which the sack will be projected from the overlying step and along which it will glide to said next lower step, and thus permitting the sack gradually to change from one form to another in descending the ladder.

MATTHEW TROY.
